Primary Examiner — Ralf Seifert*(74) Attorney, Agent, or Firm* — Dickinson Wright PLLC(57) **CLAIM**

We claim the ornamental design for a compressor for vehicles, as shown herein.

DESCRIPTION

FIG. 1 illustrates the overall form of a compressor for vehicles according to the present design;

FIG. 2 is a front view of the compressor for vehicles according to the present design;

FIG. 3 is a rear view of the compressor for vehicles according to the present design;

FIG. 4 is a left side view of the compressor for vehicles according to the present design;

FIG. 5 is a right side view of the compressor for vehicles according to the present design;

FIG. 6 is a plan view of the compressor for vehicles according to the present design; and,

FIG. 7 is a bottom view of the compressor for vehicles according to the present design.

The broken lines are included for the purpose of illustrating portions of the compressor for vehicles that form no part of the claimed design.
